(57) **CLAIM**

We claim the ornamental design for a multi-bin receptacle, as shown and described.

DESCRIPTION

FIG. 1 is a perspective view form above of a multi-bin receptacle showing our new design;

FIG. 2 is a perspective view form below thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown in the figures are included for the purpose of illustrating portions of the multi-bin receptacle and forms no part of the claimed design.

1 Claim, 7 Drawing Sheets
